AIR CUSHIONED ELEVATOR FOR
CASE PACKERS

Edward F. Rowekamp, Cincinnati, Ohio, assignor to The Lodge & Shipley Company, Cincinnati, Ohio, a corporation of Ohio

Filed Apr. 2, 1965, Ser. No. 445,138
10 Claims. (Cl. 53—247)

This invention relates to case packers. These machines are used to deposit groups of containers such as bottles in cases, the term "case" being used here in a generic sense to mean receptacles such as cartons, boxes, crates, and the like designed to receive and enclose groups of containers. More specifically, the invention is directed to an improved elevator of the type employed in case packing machines to initially receive an empty case from a conveyor, raise the case to a position to receive a group of containers, lower the filled case and then discharge the case onto a conveyor.

A typical case packer has a marshalling station to which containers are fed. At the station, they are assembled in a patterned group corresponding to the arrangement they are to have within a case. The containers are assembled on a grid having openings therein through which the containers fall as a group upon being released. Fingers extend down from each opening in the grid to serve as guides for the containers and to break their fall to a degree. In acting as guides, the fingers also insure that the containers enter the compartments of partitioned cases. Such compartments normally are used in the packing of glass articles, and particularly bottles, to prevent damage during shipment. Bottles pose a special problem in a packing operation because they have to fall a distance at least as great as their height plus the depth of the grid apparatus. This is one of the main reasons for using an elevator, because it brings the case up as close as possible to the level from which the bottles are released. Because of the fingers, the case has to be raised at least to a point where the lower ends of the fingers are within the compartments of a partitioned case when the bottles are released and then the case has to be lowered to a point where the tops of the released bottles are completely free of the fingers.

Despite the ability of existing elevators to place a case in its highest possible position relative to a grid, there is still a considerable drop for the bottles and a certain amount of breakage occurs.

The primary objective of this invention is to provide a cushioned elevator such that the shocks that bottles receive upon striking the bottom of a case is minimized, thereby reducing breakage.

It is common practice that a case packer machine be provided with adjustable parts and interchangeable parts to adapt it to assemble and deposit bottles of various sizes, capacities and shapes. Under these circumstances, it becomes necessary that the elevator upon which a case rests be made such that its upper limit of travel is adjustable. In view of this requirement, it is a further objective of this invention to provide a cushioned elevator of the type set forth in which such adjustment is exceedingly simple to make.

Other objectives and advantages of the invention will be readily apparent to those skilled in the art from the following detailed description of the drawings in which:

FIGURE 1 is a fragmentary elevational view showing, in the upper portion, the discharge end of a case packer with the elevator of this invention being shown in the lower portion of the figure. In this view, a case shown in dot-dash lines on the elevator is in its lowermost position.

2

FIGURE 2 is a view similar to FIGURE 1 showing the elevator in an elevated position with a group of bottles being inserted into the case.

FIGURE 3 is a fragmentary plan view looking down on the elevator as indicated by the line 3—3 in FIGURE 1.

FIGURE 4 is a fragmentary cross-sectional view taken on the line 4—4 of FIGURE 1.

FIGURE 5 is a fragmentary cross-sectional view taken on the line 5—5 of FIGURE 1.

FIGURE 6 is a fragmentary top plan view taken on the line 6—6 of FIGURE 2.

FIGURE 7 is a fragmentary side elevational view taken on the line 7—7 of FIGURE 2.

In FIGURES 1 and 2, there is shown the discharge end of a case packer or loader, designated generally 10, that is similar to the one disclosed in copending patent application Serial No. 318,577, filed October 24, 1963. The copending application and this application have a common assignee.

Reference is made to the copending application for the details of the machine. As shown in FIGURE 1, a group of bottles identified individually at 11 is shown marshalled upon a grid designated generally 12 ready for discharge into a case shown in dot-dash lines at 13. The case rests upon an elevator apparatus designated generally 14 that is positioned directly below the grid 12 in spaced relation thereto. A series of fingers such as those shown at 15 is associated with each opening in the grid 12, the fingers 15 converging at the lower ends to serve as guides in order to direct the bottles 11 into individual compartments within the case 13. As disclosed in the copending application, the bottles 11 are marshalled as they move onto the grid 12 in a pattern that corresponds to the arrangement of the partitions within the case 13 and upon their release the bottles 11 are free to drop through the fingers 15 at a time when the case 13 is elevated into the position shown in FIGURE 2.

The elevator 14 includes a base or frame 16 having a support portion 17 on one side thereof. A pair of horizontally spaced guide rods 18 and 19 extend upwardly from the support portion 17 of the base 16.

An elevator platform 20 has one end slidably mounted on the guide rods 18 and 19 by sleeves 21 and 22. By this arrangement, the elevator platform 20, which is preferably of cast construction, is mounted in cantilever fashion.

The base 16, which also is preferably of cast construction, includes a pair of spaced, parallel side walls 23 and 24 (see FIGURES 3 and 6). The side wall 23 is disposed adjacent the support portion 17 of the base 16. An end wall 25 joins one end of each of the side walls 23 and 24 together. The side walls 23 and 24 also are connected intermediate their ends by a connecting wall 26 (see FIGURES 5 and 6).

Four live rollers 27 are supported by the base 16 in spaced relation to each other. Each of the rollers 27 is attached to a shaft 28 having one end journaled in a bearing support 29, which is attached to the top of the side wall 23. The other end of the shaft 28 extends through a bearing support 30, which is attached to the top of the side wall 24. Each of the shafts 28 has a chain sprocket 31 (see FIGURE 4) attached to the end extending beyond the bearing support 30 whereby all of the rollers 27 are rotated in the same direction and at the same speed.

The elevator platform 20 has a depressed floor 32 on which the case 13 is supported when the elevator platform 20 is moved upwardly from its lowermost position of FIGURE 1. However, when the elevator platform 20 is in its lowermost position, the floor 32 does not

contact the case 13 as shown in FIGURE 1 but the case 13 is supported on the live rollers 27.

The floor 32 of the elevator platform 20 has two parallel slots 33 (see FIGURES 3 and 5) formed therein to permit the tops of the two center rollers 27 to extend above the surface of the floor 32. The floor 32 of the elevator platform 20 terminates short of the two end rollers 27. Thus, all of the rollers 27 have their top surfaces positioned above the floor 32 of the elevator platform 20 when the elevator platform 20 is in its lowermost position.

While the floor 32 of the elevator platform 20 has been shown as depressed, it should be understood that the floor 32 need not be depressed for cooperation with the rollers 27. This depressed arrangement of the floor 32 is to permit clearance of the bottom of each side 34 and 35 of the elevator platform 20 with respect to the bearing supports 29 and 30. Thus, by appropriate arrangement, the floor 32 would not be depressed; one example would be to increase the diameter of the rollers 27.

The elevator platform 20 has an L-shaped bracket 36 attached to the top of the side 34 by bolts 37. The bolts 37, which are fixed to the platform 20, extend through longitudinal slots 39 in the base of the bracket 36 whereby the bracket 36 may be adjusted longitudinally with respect to the platform 20 and the rollers 27. The bracket 36 functions as a guide for one side of each of the cases 13 as it is moved by the rollers 27.

The bracket 36 has an elevator gate 40 pivotally connected to its base by a pin 41. Thus, the elevator gate 40 moves with the bracket 36 when the position of the bracket 36 is adjusted.

The elevator gate 40 functions to stop the case 13 as it is advanced by rotation of the rollers 27. Therefore, the longitudinal adjustment of the bracket 36 is to position the elevator gate 40 in accordance with the length of the case 13.

As shown in FIGURE 3, the bracket 36 is positioned for the longest of the cases 13. If the cases 13 are shorter, the bracket 36 is adjusted by releasing the nuts 38 and sliding the bracket 36 relative to the bolts 37. It should be understood that the longest of the cases 13 is used with the bottles 11 of largest diameter.

The elevator gate 40 prevents the empty case 13, which is moved by the rollers 27 due to their rotation, from being moved beyond the elevator 14. Thus, when an empty case 13 engages the elevator gate 40, it is ready to be raised to the position in which it receives the bottles 11 from the case packer 10.

As best shown in FIGURE 3, a resiliently biased sensing finger 42 is provided in close association with gate 40. As will be explained in greater detail, the sensing finger 42 controls two operations in the machine. When a case moves into the elevator and makes contact with the finger, gate 40 is swung closed. In addition, pressurized air from a suitable pressure source (not shown) is directed through a hose 44 (see FIGURE 7) to an air cushion means 45. The sensing finger 42 operates an electrical switch 43, switch 43 having appropriate contacts in circuitry to accomplish the two functions of the finger 42.

The air cushion means 45 includes a plurality of connected annular air springs 46, which are well-known. The lower end of the air cushion means 45 is attached to the support portion 17 of the base 16 while the upper end of the air cushion means 45 is attached to the elevator platform 20 between the sleeves 21 and 22.

Accordingly, when the sensing finger 42 is pivoted by the case 13 to actuate the switch 43, the supply of air to the air cushion means 45 causes upward movement of the elevator platform 20 along the guide rods 18 and 19. As the elevator platform 20 moves upwardly, the floor 32 engages the bottom of the case 13, which has been resting on the live rollers 27, to remove the case 13

from the rollers 27 and support it on the floor 32 of the platform 20 for movement therewith.

The elevator platform 20 has a clamping assembly 47, which is mounted on the top of the side 35 of the platform 20. As shown in FIGURE 3, the clamping assembly 47 is H-shaped when viewed from above. The clamping assembly 47 includes a pair of parallel tie plates 48 and 49, which are joined together intermediate their ends by a transverse tie plate 50 to form the H-shape.

The clamping assembly 47 includes a hollow tube 51, which is secured to one end of each of a pair of horizontally spaced threaded rods 52. This allows lateral adjustment of the hollow tube 51 with respect to the plate 48.

The clamping assembly 47 is secured to the elevator platform 20 by bolts 53 and nuts 54. Each of the bolts 53 extends through the plate 48, an upstanding lug 55 on the elevator platform 20, and the plate 49. A spring 56 surrounds each of the bolts 53 between the plate 48 and the upstanding lug 55.

The hollow tube 51 grips each of the cases 13 as the elevator platform 20 moves upwardly to permit transfer of the case 13 from the rollers 27 to the floor 32. The spring biased tube 51 is permitted to be moved into engagement with the case 13 by a cam 57, which is attached to the base 16 and extends through a slot 58 in the side 35 of the elevator platform 20, cooperating with a roller 59, which functions as a cam follower to maintain the clamping tube 51 disengaged from the case, 30 on the plate 50 of the clamping assembly 47.

As shown in FIGURE 2, the cam 57 has an upwardly slanting surface 60, which allows the springs 56 to move the clamping assembly 47 towards the case 13 as the elevator platform 20 moves upwardly. The springs 56 are constantly urging the tube 51 toward the case 13. Thus, the tube 51 grips one side of the case 13 and cooperates with the bracket 36 to lock the case 13 in position on the floor 32 of the elevator platform 20.

Accordingly, a positive locking arrangement is employed to insure that the case 13 remains in position on the elevator platform 20 during upward movement thereof. Furthermore, the cooperation with the cam 57 insures that this gripping or locking occurs after there is relative movement in an upward direction between the base 16 and the platform 20 so that locking of the case 13 occurs only after the case 13 ceases to be supported on the rollers 27.

Because of the resiliency of the springs 56, the hollow tube 51 is automatically positioned to compensate for any variance in width of the case 13. However, the primary adjustment, when the width of the case 13 is changed, is by adjusting the rods 52 with respect to the plate 48.

When pressurized air is directed to air cushion means 45, the elevator platform 20 is moved upwardly to a place where it abuts two rubber cushioning devices 61-61 that are fastened by known means to the two support rods 18 and 19 just underneath a tie bar 62 that connects the upper ends of the two rods 18 and 19. The two cushions 61-61 determine the upper limit of travel of the elevator and when adjustment in the overall length of travel of the elevator is required for bottles of different sizes, cushions of different height may be substituted for those shown. The amount of air pressure required to lift the elevator is dependent upon the weight that is to be lifted and it is found that light weight cases can be lifted with as little as five pounds of air pressure. With the heaviest wooden cases, an air pressure of approximately twelve to thirteen pounds may be required. In any event, as will be explained, the descent of the elevator is timed such that the air pressure within the cushion is substantially less than either of the above figures when bottles being received in the case strike the bottom of the case.

Attention is now directed to the electrical switch designated 63 that is mounted on base 16 underneath the ele-

vator platform. This switch has an arm 64 with a roller 65 at the outer end thereof. When the elevator is in its lowermost position, the roller 65 is contacted by the underside of the elevator, as best shown in FIGURE 1, to actuate switch 63. As the elevator platform 20 is moved upwardly by the air cushion means 45, the arm 64 is permitted to swing up into the position shown in FIGURE 2. Switch 63 has two sets of contacts, one set of which becomes effective upon the release of arm 64 by the raising of the elevator and the other set of which becomes effective upon the lowering of arm 64 as the elevator moves into its lowermost position. The first set of contacts is closed as the elevator starts up and cooperates with controls for an air cylinder 66, a timer 67, and a switch 68 that is mounted on the case packer 10. The switch 68 is closed only when the bottles 11 have completely filled the grid 12. As more fully explained in the copending application, the bottles 11 move into the grid on support bars (not shown). The purpose of the air cylinder 66 is to shift all of the support bars laterally so that the bottles can fall from the grid into a waiting case. Timer 67 which is shown diagrammatically only in FIGURE 1, is wired into the machine such that it does three things. The timer completes the circuit to a solenoid operated valve that directs air under pressure to cylinder 66 so that the cylinder shifts the support bars laterally, permitting the bottles to drop from the grid. Secondly, it completes a circuit to a solenoid operated valve that exhausts the air from air cushioning means 45 which permits the elevator to descend. It also completes a circuit which, as will be explained, opens gate 40. However, the timer is tied in with the switch 68 so that it cannot become effective to do any of the above three things unless the circuit has been closed at switch 68 thus insuring that the grid is full of bottles before the drop occurs. Additionally, the timer is tied electrically with switch 63 so that it is conditioned to start timing as the elevator starts up. The purpose of tying the timer in to switches 63 and 68 will be more fully explained below. Generally, however, it makes the machine adaptable to operations at various speeds depending upon the requirements of a particular packing operation. For this purpose, the timer is adjustable. In any event, once the timer has ticked off whatever time has been set thereon, the dropping of the bottles occurs simultaneously with the exhausting of the air pressure in air cushioning means 45 so that the dropped bottles hit the case into which they fall with the air cushioning means 45 in "soft" condition. The continued exhausting of the air from the air cushioning means 45 results in cushioned downward movement of the elevator platform 20 such that the bottles are not subjected to jarring when the elevator reaches its lowermost position. Additional cushioning if needed is provided when the elevator platform 20 reaches its lowermost position by resilient pads 69-69 which surround the guide rods 18 and 19.

As stated, the timer closes a circuit to a solenoid that directs air under pressure to an air cylinder 70 (see FIGURE 3) that is mounted upon the bracket 36 on the elevator platform 20. It must be kept in mind however that the timer cannot function to direct air to cylinder 70 unless switches 63 and 68 have been preconditioned, one, by the elevator being in raised position and two, by a full complement of bottles being present in the grid. Thus, when the timer is readied and switches 63 and 68 are closed, one solenoid of a double solenoid valve 71 is actuated whereby air is supplied to the air cylinder 70 to cause retraction of its piston rod 72. Piston rod 72 has a clevis 73 attached at its outer end. The clevis 73 is pivotally connected by pin 74 to the elevator gate 40. Thus, when air is supplied to the cylinder 70 to retract the piston rod 72, the elevator gate 40 is pivoted about the pin 41 to move the elevator gate 40 from its blocking position to an open position. The gate 40 could be operated by an instrumentality other than the timer, for example,

the double solenoid valve 71 could be tied in with switch 63, which opens as the elevator moves into its lowermost position. However, it is found that a faster operation is possible by having the gate open when the elevator is raised.

As the elevator platform 20 moves downwardly, it can be seen that the loaded case 13 comes into contact with the live rollers 27, these rollers projecting up above the surface of the platform so that driving contact between the rollers and the bottom of the case is established before the platform is all of the way down. Since the gate 40 is in its open position, the loaded case 13 is immediately driven from the elevator onto a conveyor line (not shown) or other suitable receiving means.

When the loaded case 13 leaves the elevator platform, the resiliently biased sensing finger 42 swings out into the path of an oncoming case ready to be contacted to effect the closing of the gate and thereby block the case. When the sensing finger swings in, switch 43 being tied in with the double acting solenoid valve 71 results in air being supplied to the cylinder 70 to extend the piston rod 72. This extension of the piston rod 72 returns the elevator gate to its blocking position.

In order that another empty case 13 will always be available for movement into the rollers 27 after the loaded case 13 has been removed therefrom, a conveyor belt 75 is disposed in alignment with the rollers 27 as shown in FIGURE 3. The conveyor belt 75 is constantly driven by a motor 76.

The motor 76 is connected to a shaft 77 of a chain sprocket 78 through a speed reducer 79. A chain 80 connects the sprocket 78 with a chain sprocket 81. The sprocket 81 is mounted on one end of a shaft 82, which extends between the top and bottom of the conveyor belt 75. The shaft 82 has a pulley 83, which is in engagement with the conveyor belt 75 (see FIGURE 5) to drive the conveyor belt 75, mounted thereon.

The shaft 82 is also connected to a chain sprocket 84, which has a continuous chain 85 (see FIGURE 4) passing therearound. The chain 85 also passes around the chain sprockets 31 on the ends of the roller shafts 28 whereby the rollers 27 are driven at the same speed as the speed of the conveyor belt 75. This insures that the cases 13, which are moved along the conveyor belt 75, will not be advanced at a different speed when they are picked up by the rollers 27.

A chain take-up plate 86 is attached to a portion of the side wall 24 of the base 16 by bolts 87 extending through slots 88 in the member 86. The plate 86 has a chain sprocket 89 rotatably mounted thereon. Thus, by adjusting the position of the plate 86 through movement with respect to the bolts 87, which are fixed to the side wall 24, the chain 85 is tightened as required to provide the desired drive of the rollers 27.

A shroud 90 is attached to the side walls 23 and 24 by suitable means (not shown) and extends rearwardly therefrom. The shroud 90 is formed with an open center through which the conveyor belt 75 passes as shown in FIGURE 3.

An L-shaped bracket 91, which functions as a guide rail for one side of the cases 13, is adjustably mounted on one side of the shroud 90. Bolts 92, which are fixed to the shroud 90, extend through slots 93 in the bracket 91 and have nuts 94 on their ends to retain the bracket 91 in position.

The position of the bracket 91 is varied by movement of the bracket 91 with respect to the bolts 92 in accordance with the width of the case 13. As shown in FIGURE 3, the bracket 91 is positioned for the largest width of the cases 13. As the diameter of the bottles 11 decreases, the width of the case 13 decreases. The bracket 91 is moved toward the conveyor belt 75 as the width of the case 13 becomes smaller.

An L-shaped bracket 95 is fixed to the shroud 90 on the other side of the conveyor belt 75 from the bracket

91. A conveyor gate 96 is disposed adjacent the end of the conveyor belt 75 to stop movement of each of the cases 13 as it nears the end of the conveyor belt 75. The conveyor gate 96 is attached to one end of a plate 97, which is pivotally mounted on the bracket 95 by a pin 98. The other end 99 of the pivotal plate 97 is pivotally connected to a clevis 100 by a pin 101. The clevis 100 is attached to one end of a piston rod 102 of an air cylinder 103.

When air is supplied to the cylinder 103 to cause extension of the rod 102, the pivotal plate 97 is moved to the dot-dash position of FIGURE 3. In this dot-dash position, the conveyor gate 96 is moved out of the path of the case 13 on the belt 75 while the other end of the pivotal plate 97 passes through a slot 104a in the L-shaped bracket 95. This end of the pivotal plate 97 has a cover 104 thereon of a flexible material.

Since the bracket 95 functions as a guide rail for one side of each of the cases 13 moved by the conveyor belt 75, the movement of the pivotal plate 97 to the dot-dash position of FIGURE 3 results in the end having the cover 104 engaging the next of the cases 13 to prevent movement of the next of the cases 13 by the belt 75.

Thus, when one of the cases 13 is advanced from the belt 75, to the rollers 27, the protruding end of the pivotal plate 97 prevents the next of the cases 13 from moving forward until the conveyor gate 96 has returned to its stopping or blocking position. The flexible material of the cover 104 functions to permit the pivotal plate 97 to move into engagement with the case 13 without damage thereto.

To adapt the elevator of this invention to fast speeds it is found expedient to swing the pivotal plate 97 to the dot-dash, open position of FIGURE 3 at the instant that the elevator reaches its lowermost position. When this happens, the arm 64 on switch 63 is depressed. The second set of contacts in switch 63 is in a circuit to a solenoid operated valve that shifts cylinder 103 to swing the conveyor gate 96 out of the way of the case next to come onto the elevator. Thus, the oncoming empty case closely follows the outgoing full case and time is saved in getting the oncoming empty case into a position such that it contacts sensing finger 42 to start the elevator up and close gate 40.

The set of contacts of switch 63 that close when the elevator is down is in series in a circuit with a normally open switch 108, which is moved to its closed position by a resiliently biased sensing finger 109. Sensing finger 109 is moved from its position of FIGURE 3 when there is a case 13 in engagement with the conveyor gate 96.

Thus, the pivotal gate 97 cannot be moved to the open, dot-dash position of FIGURE 3 until two conditions are met. One is that a case is in contact with conveyor gate 96, being held on the conveyor in readiness to enter the elevator. The other of the conditions is that the elevator platform 20 is in its lowermost position ready to receive the oncoming case as soon as it is released.

The opening of the switch 108 results in air being supplied to the cylinder 103 so that the piston rod 102 is retracted therein. This returns the pivotal plate 97 to the solid line position of FIGURE 3 wherein the next of the cases 13 on the conveyor belt 75 may be advanced forwardly until it reaches the conveyor gate 96.

At this time, the sensing finger 109 is again moved inwardly to close the switch 108. However, by this time, the switch 63 is opened because the elevator platform 20 has started to move upwardly. Thus, the air cylinder 103 cannot be actuated so that the case 13 on the conveyor belt 75 awaits the return of the elevator platform 20 to its lowermost position to indicate that the case 13 on the rollers 27 has been loaded and removed therefrom.

When the sensing finger 109 is moved inwardly by one of the cases 13 to close the switch 108, the closing of the switch 108 also results in air being supplied to an air cylinder 110. The air cylinder 110 has a piston rod 111 extending therefrom and attached to a clevis 112.

The clevis 112 is attached to one end of a plow 113 by a pin 114. The plow 113 is pivotally mounted by a pin 115 on support bracket 116.

When air is supplied to the air cylinder 110 by closing 5 of the switch 108, the piston rod 111 is retracted. This moves the plow 113 to the position shown in FIGURE 3 wherein it causes the forward flap of the case 13, which is held by the conveyor gate 96, to be moved to an open position.

The plow 113 opens the rear flap of the case 13 as the case 13 advances from the conveyor belt 75 to the rollers 27. When the sensing finger 109 returns to the 10 position of FIGURE 3, the switch 108 is opened to cause air to be supplied to the air cylinder 110 to extend the piston rod 111 whereby the plow 113 is moved toward the sensing finger 109.

The space between the conveyor belt 75 and the first of the rollers 27 is bridged by a dead plate 117 (or a roller may be used if desired), which is attached by 20 suitable means (not shown) to the shroud 90. However, as shown in FIGURES 4 and 5, the dead plate 117 is disposed slightly beneath the tops of the belt 75 and the rollers 27.

It should be understood that the side flaps of each of 25 the cases 13 are opened by suitable means (not shown) prior to the case 13 engaging the conveyor gate 96. One of the side flaps is maintained in an open position by a plate 118 (see FIGURES 2 and 3) when the case 13 is on the rollers 27 or the elevator platform 20. The other of the side flaps of the case 13 is held in an open position by a plate 119 when the case 13 is on the rollers 27 or the elevator platform 20.

The plate 118 is attached to the elevator platform 20 by a pair of upstanding lugs 120 and 121 (see FIGURE 35 35). A plate 122 is positioned on top of the lugs 120 and 121 with the plate 118 spaced therefrom by spacers 123. The spacing relation of the plates 118 and 122 permits side flaps on the cases 13 of various heights to be retained in an open position.

The plate 119 is connected by two spaced threaded 40 rods 124 to blocks 125 (see FIGURES 1 and 4), which are slideable on rods 126 extending upwardly from the lugs 55. Thus, the position of the plates 119 may be adjusted in a vertical direction in accordance with the height of the case 13.

A plurality of leveling pads 127 are employed to level 45 the elevator 14 and the conveyor belt 75 and the related structure. A guard 128, which is attached to the side wall 24, is positioned over the continuous chain 85, the chain sprockets 31, and other related structure to protect them.

Considering the operation of the present invention, the bracket 91 will be positioned to fit the width of the cases 13, which are being loaded by the case packer 10. Likewise, the bracket 36 will be positioned in accordance 55 with the length of the cases 13.

With one of the cases 13 positioned on the rollers 27 against gate 40 air is directed to air cushioning means 45 and the elevator platform starts upwardly. At this time, the next case to be received by the elevator is in position 60 at conveyor gate 96. Sensing arm 109 is swung back and the circuit, to be triggered by switch 63 when the elevator platform returns to its lowermost position, is readied to insure that gate 96 moves out of the way just as soon as the elevator comes down. Until such time, conveyor gate 96 holds the case in its position of readiness.

The first part of the upward movement of the elevator causes the clamp bar 51 to move inwardly 65 under the action of springs 56—56 against one side of the case insuring that its position is in alignment with the grid above it. If at any time during the upward movement of the platform, the switch 68 closes as a result of a full complement of bottles being in the grid, the tie-in between switch 63 and switch 68 starts the 70 timer 67. When timed out, the timer closes the circuit 75

to the solenoid operated valve that controls the actuation of air cylinder 66 and the bottles drop into the case.

The speed at which the elevator platform moves upwardly is a function of the speed at which air is permitted to enter the air cushioning means 45. This is readily adjustable by known means such as an adjustable valve in the line through which air flows to the air cushioning means. Thus, the adjustable timer 67 can be adjusted relative to the air entering the air cushioning means to insure that bottles are never dropped at a time when the elevator is still rising. Rather relative adjustments are made in the timer 67 and the valve in the air line 44 leading to the air cushioning means to insure that the elevator is either at its uppermost position, ready to retract from that position, or actually retracting as the bottles strike the bottom of the case. The last set of conditions is the preferred way in which the machine is operated.

In some packer lines in small plants it is desirable to have the machine operate slowly and in large plants, very rapidly. It is found that the machine of this invention is readily adaptable to either type operation. Time is saved by having an oncoming case move onto the elevator platform the instant that it moves into its lowermost position and while the filled preceding case is moving off. Further time is saved by tying in switch 63 to switch 68 and with the timer so that there is no lost motion or waiting for the drop to occur. However, by providing the adjustable timer and having the same tie-in between the switch 68 and the timer 67, slow operations are accommodated because at no time can a bottle drop occur unless switch 68 is satisfied, being closed by a full complement of bottles.

Thus, it may be seen that I have fulfilled the objectives of the invention by providing a fully automatic, highly adaptable case elevator that is cushioned by air to reduce bottle damage to a minimum. For purposes of exemplification, a particular embodiment of the invention has been shown and described according to the best present understanding thereof. However, it will be apparent that changes and modifications in the arrangement and construction of the parts thereof may be resorted to without departing from the spirit and scope of the invention.

Having described my invention, I claim:

1. An apparatus for positioning a case to receive bottles from a case packer or the like, said apparatus including a base, an elevator platform mounted above said base and movable relative thereto in a vertical direction, air cushion means having one end connected to said base and the other end connected to said elevator platform, said base having means to support an empty case thereon, means to cause pressurized air to be supplied to said air cushion means to move said elevator platform upwardly after an empty case is positioned on said support means, means permitting transfer of an empty case from said support means to said elevator platform, means to lock an empty case in position on said elevator platform, means to cause removal of said pressurized air from said air cushion means when said elevator platform reaches its uppermost position whereby said elevator platform returns to its lowermost position, said last mentioned means simultaneously allowing release of bottles from said case packer to fall by gravity into an empty case on said elevator platform, and means to release said case locking means before said elevator platform reaches its lowermost position, said transfer permitting means allowing transfer of the loaded case from said elevator platform to said support means.

2. An apparatus for positioning a case to receive bottles from a case packer or the like, said apparatus including a base having a plurality of rollers mounted thereon, means to continuously rotate said rollers in one direction, an elevator platform mounted above said base, air cushion means having one end connected to said base and the other end connected to said elevator platform, means to

direct an empty case onto said rollers in a direction for advancement by said rollers, means to limit case movement on said rollers in the advancing direction, means to cause pressurized air to be supplied to said air cushion means to move said elevator platform upwardly after said rollers have an empty case positioned thereon, said elevator platform receiving an empty case from said rollers, means to lock a case on said elevator platform, means to cause removal of pressurized air from said air cushion means when said elevator platform reaches its uppermost position whereby said elevator platform returns to its lowermost position, said last mentioned means simultaneously allowing release of bottles from the case packer to an empty case on said elevator platform, means to release said case locking means before said elevator platform reaches its lowermost position, said rollers being disposed to receive the loaded case on said elevator platform, and means to move said case limiting means from its limiting position before said rollers receive the loaded case from said elevator platform.

3. An apparatus for positioning a case to receive bottles from a case packer or the like, said apparatus including a base having a plurality of rollers mounted thereon, means to continuously rotate said rollers in one direction, an elevator platform mounted in spaced vertical relation to said base, air cushion means having one end connected to said base and the other end connected to said elevator platform, means to direct an empty case onto said rollers in a direction for advancement by said rollers, means to limit case movement on said rollers in the advancing direction, means to cause air to be supplied to said air cushion means to move said elevator platform upwardly after said rollers have an empty case positioned thereon, said elevator platform receiving an empty case from said rollers after upward movement of said elevator platform relative to said rollers begins, means to cause removal of air from said air cushion means when said elevator platform reaches its uppermost position whereby said elevator platform returns to its lowermost position, said last mentioned means simultaneously allowing release of bottles from the case packer to an empty case on said elevator platform, said rollers being disposed to receive the loaded case on said elevator platform before said elevator platform reaches its lowermost position, and means to move said case limiting means from its limiting position before said rollers receive the loaded case from said elevator platform during its downward travel.

4. An apparatus for positioning a case to receive bottles from a case packer or the like, said apparatus including a base having a plurality of rollers mounted thereon, means to continuously rotate said rollers in one direction, an elevator platform mounted in spaced vertical relation to said base, air cushion means having one end connected to said base and the other end connected to said elevator platform, means to direct an empty case onto said rollers in a direction for advancement by said rollers, means to limit case movement on said rollers in the advancing direction, means to cause air to be supplied to said air cushion means to move said elevator platform upwardly after said rollers have an empty case positioned thereon, said elevator platform having a floor for receiving an empty case from said rollers after upward movement of said elevator platform relative to said rollers begins, the floor of said elevator platform being disposed beneath said rollers in the lowermost position of said elevator platform, said floor of said elevator platform being constructed to permit relative movement in a vertical direction of said floor and said rollers, means to cause removal of air from said air cushion means when said elevator platform reaches its uppermost position whereby said elevator platform returns to its lowermost position, said last mentioned means allowing release of bottles from the case packer to an empty case on the floor of said elevator platform, said rollers being disposed to receive the loaded case on the floor of said elevator platform

before said elevator platform reaches its lowermost position, and means to move said case limiting means from its limiting position before said rollers receive the loaded case from said elevator platform during its downward travel.

5. In case packing apparatus having a base, a grid mounted above said base through which bottles may be dropped, means for supplying bottles to said grid, and a case supporting elevator mounted below said grid for vertical movement, the improvement comprising, resilient means defining an enclosed expandable chamber connected between said base and said elevator, an air supply connected to said expandable chamber, and means for controlling the supply of air to said expandable chamber to raise and lower said elevator in timed relation to the dropping of bottles through said grid, said controlling means including means for exhausting air from said expandable chamber at least as soon as the bottles strike the case.

6. Case packing apparatus according to claim 5 in which said resilient means defining said enclosed chamber is characterized by expanding to an extended position upon the application of air pressure to the inside of said chamber and, as a result of the resiliency of said means defining said chamber, forcibly returning to a retracted position upon the release of said air pressure from said chamber.

7. In a case packing apparatus having a base, a grid mounted above said base through which bottles may be dropped, means for supplying bottles to said grid, and a case supporting elevator mounted below said grid for vertical movement, the improvement comprising expandable means to raise and lower said elevator, said expandable means having walls defining an enclosed chamber connected between said base and said elevator, at least part of said walls being resilient and characterized by permitting said chamber to expand upon the application of air pressure thereto and forcibly collapsing said chamber upon the release of air pressure therefrom, an air supply connected to said chamber, and means for controlling the supply of air to said chamber, said controlling means including means for exhausting air from said expandable chamber to retract said elevator at least as soon as the bottles strike the case.

8. In case packing apparatus having a base, a grid 45 mounted above said base through which bottles may be

dropped, means for supplying bottles to said grid, and a case supporting elevator mounted below said grid for vertical movement, the improvement comprising means having a first, rigid end wall connected to said elevator and a second, rigid end wall connected to said base, said means having other walls that define with said end walls an enclosed expandable and retractable chamber, at least a part of said other walls being resilient, an air supply connected to said chamber, and means for controlling the supply of air to said chamber, said controlling means including means for exhausting air from said expandable chamber to retract said elevator at least as soon as the bottles strike the case.

9. Case packing apparatus as set forth in claim 8 in which said other walls are disposed symmetrically about a central axis.

10. In a case packing apparatus having a base, a bottle grid mounted above said base, means for supplying bottles to said grid, and an elevator mounted on said base for vertical movement, the improvement comprising resilient walled means defining an expandable and retractable chamber interposed between said base and said elevator, an air supply connected to said chamber, and means for controlling the supply of air to said chamber to raise and lower said elevator, said controlling means including means for exhausting air from said expandable chamber to retract said elevator at least as soon as the bottles strike the case.
